US00D598378S

(12) United States Design Patent
Lannoch

(10) Patent No.: US D598,378 S
(45) Date of Patent: * Aug. 18, 2009

(54) HOUSING COVER FOR MOTOR ELECTRONICS

D424,516 S * 5/2000 Friedrichsen D13/112
D492,252 S * 6/2004 Su D13/112
D525,195 S * 7/2006 Palese D13/112

(75) Inventor: Hans-Juergen Lannoch,
Linkenheim-Hochstetten (DE)

* cited by examiner

(73) Assignee: SEW-Eurodrive GmbH & Co., KG,
Bruchsal (DE)

Primary Examiner—Prabhakar Deshmukh

Assistant Examiner—Derrick Holland

(74) Attorney, Agent, or Firm—Kenyon & Kenyon LLP

() Term: 14 Years

(57) CLAIM

(21) Appl. No.: 29/323,967

The ornamental design for a housing cover for motor electronics, as shown and described.

(22) Filed: Sep. 3, 2008

DESCRIPTION

(30) Foreign Application Priority Data

Mar. 4, 2008 (DE) 40 2008 001 260

(51) LOC (9) Cl. 13-01

(52) U.S. Cl. D13/122

The Figures include an illustration of the logo, "SEW," and other written matter, which is shown for illustrative purposes and forms no part of the claimed design.

FIG. 1 is a perspective view of a housing cover for motor electronics showing my new design;

FIG. 2 is a front view thereof;

FIG. 3 is a left side view thereof;

FIG. 4 is a rear view thereof;

FIG. 5 is a right side view thereof; and,

FIG. 6 is a top view thereof.

The Figures include an illustration of the logo, "SEW," and other written matter, which is shown for illustrative purposes and forms no part of the claimed design.
